US00D986170S

(12) **United States Design Patent** (10) Patent No.: **US D986,170 S**
(45) Date of Patent: ** *May 16, 2023

(54) **POWER SUPPLY UNIT**

(71) Applicant: **EcoFlow Inc.**, Shenzhen (CN)

(72) Inventors: **Lei Wang**, Shenzhen (CN); **Haibin Zheng**, Shenzhen (CN)

(73) Assignee: **ECOFLW INC.**, Shenzhen (CN)

(*) Notice: This patent is subject to a terminal disclaimer.

(**) Term: **15 Years**

(21) Appl. No.: **35/512,137**

(22) Filed: **Jun. 16, 2021**

(80) **Hague Agreement Data**

Int. Filing Date: **Jun. 16, 2021**

Int. Reg. No.: **DM/215028**

Int. Reg. Date: **Jun. 16, 2021**

Int. Reg. Pub. Date: **Jul. 9, 2021**

(30) **Foreign Application Priority Data**

Dec. 24, 2020 (CN) 202030799517.8

(51) **LOC (14) Cl.** **13-03**

(52) **U.S. Cl.**

USPC **D13/110**

(58) **Field of Classification Search**

USPC D13/110, 112, 107, 108, 103; D21/333
See application file for complete search history.

PLLC

(57) **CLAIM**

The ornamental design for a power supply unit, as shown and described.

DESCRIPTION

1. Power supply unit

1.1 : Front

1.2 : Back

1.3 : Left

1.4 : Right

1.5 : Top

1.6 : Bottom

1.7 : Perspective

1.8 : Perspective

1.9 : Perspective

1.10 : Perspective

No. 1.1 for front view; No. 1.2 for back view; No. 1.3 for left view; No. 1.4 for right view; No. 1.5 for top view; No. 1.6 for bottom view; No. 1.7 for perspective view (front, top, right side); No. 1.8 for perspective view (back, bottom, left side); No. 1.9 for perspective view (front, bottom, left side); No. 1.10 for perspective view (back, top, right side).

1 Claim, 10 Drawing Sheets
